UNITED STATES PATENT OFFICE.

CHARLES B. LEFFERT, OF CHICAGO, ILLINOIS, ASSIGNOR TO UNITED STATES TENT & AWNING COMPANY, OF CHICAGO, ILLINOIS, A CORPORATION OF ILLINOIS.

TENT.

Application filed June 4, 1924. Serial No. 717,731.

My invention relates generally to improvements in tents but relates more particularly to improvements in so called umbrella tents.

The general object of my invention is to provide an umbrella tent of such construction that there shall be available for use the greatest amount of space.

It is also an object of my invention to provide a tent of this kind which shall be so constructed that it shall be better adapted to withstand the varying conditions to which it is subjected in use.

Another object of my invention is to provide a tent of this character which shall be of such construction that it can be quickly and easily erected, even by one person and which shall be rigid and weathertight when erected.

I aim also to provide a structure which can be used with or without a center pole, as desired.

My invention consists generally in a tent of the form, arrangement, construction and co-operation of the parts whereby the above named objects, together with others that will appear hereinafter, are attainable, and my invention will be more readily understood by reference to the accompanying drawings which illustrate what I consider, at the present time, to be the preferred embodiment thereof.

In said drawings:

Fig. 1 is a perspective view of a tent embodying my invention.

Fig. 2 is a detail view of the top of the frame structure.

Fig. 3 is a detail view of the outer brace construction.

Fig. 4 is a transverse vertical section through the tent.

Fig. 5 is a detail sectional view of the frame structure at the juncture of the tent side and top.

Fig. 6 is a detail view, partly in section and partly in elevation of the telescopic tent poles; and

Fig. 7 is a sectional view substantially along the line 7—7 of Fig. 6.

It has long been desirable to provide a tent which would be compact so that it could easily be carried, say on the running board of an automobile, which should be of such construction that it could be quickly and easily erected so that it could be

used by auto campers or others who usually break camp frequently and which should be rigid and durable.

I have devised such a tent and which in use has proven to be admirably adapted to such requirements.

Referring now to the drawings for the details of construction, the walls of the tent, of which there are four in the illustrated construction, bear the reference character 1. They preferably extend in a generally upright direction but also inwardly slightly. The top 2 is composed of four substantially triangular pieces which meet at the center and which extend downwardly and outwardly, being joined to the walls along the line 3.

The tent frame work comprises four telescopic poles 4, of special construction, which are arranged at the four corners of the tent. Supported thereon is a substantially horizontally disposed frame work composed of four arms 5 which, at their outer ends are pivotally secured to bracket members 6 at 6a. The bracket members 6 have shank portions 7 which fit into the top member of the telescopic poles 4.

Also secured to the bracket members 6, as by means of the pins 9, are a plurality of upwardly and inwardly extending members 8. The upper ends of the members 8 are secured to the fixture 10 by means of the pins 11. The fixture 10 is secured to a centrally and vertically arranged short pole member 12 which, at its upper end, extends through a grommet 13 in the center of the top of the tent and which, at its lower end, extends a short distance below the plane of the arms 5.

Slidably mounted on the short pole member 12 is a sleeve 14 provided with four pairs of ears 15 to which the inner ends of the arms 5 are secured as by means of the pins 16. The inner end portions 17 of the arms 5 are provided with elongated slots 18 through which the pins 16 extend. This construction permits movement of the arms inward until the extreme ends or tips 19 engage the short center pole 12. The canvas of the tent, being in a stretched condition, causes inward pressure on the arms 5, causing them automatically to clutch the short center pole. In this manner a frame construction is provided wherewith proper

support is given without the necessity of the usual center pole support from the ground. The tent space is, therefore, better adapted for use.

5 The brackets 6 are held in place by a hook portion 20 which extends through a grommet 21 which are preferably located at the corners of the tent, and where the top and sides meet. This hook portion also 10 serves as a convenient means of attaching guy or staying ropes, if desired.

15 I preferably provide means for conveniently locking the telescopic poles 4 in desired condition. The details of this mechanism are best shown in Figs. 6 and 7. Secured to the upper end of the lower pole member 4 is a sleeve like member 22, the center bore 23 of which is of such size that it makes a nice sliding fit with the upper 20 pole member 4'. It will be understood that the upper pole member 4' telescopes within the lower pole member 4. To lock the poles 4 and 4' in any set position a slideable member 24 is provided. It has a curved face 25 adapted to engage the pole member 4'. The member 22 is provided with two vertically inclined faces 26, against which face portions 27 of the member 24 abut. By moving the member 24 downwardly it is pressed 30 tightly against the pole member 4 and by movement upwardly it is backed away, thus freeing the pole so that it can be removed entirely, or shifted to any desired position. A finger grip portion 28 is provided on the 35 member 24 for convenient manipulation. The portion 28 is of such size that it can be conveniently tapped or struck with a stick, stone or almost any available device in case it is necessary to fasten it more tightly 40 than can be done with the hands or to release it.

To erect the tent a convenient method of procedure is to stake down the four corners, then to insert the short pole 12 into 45 the central opening in the top of the tent and to insert the hooked ends 20 of the brackets 6 through the respective grommets 21. In this manner the frame structure composed of the arms 5, members 8 and short 50 pole 12 are arranged within the top of the tent and while it is still limp or on the ground. As a next operation, one of the telescopic poles 4 is placed through the door or opening 30 of the tent and telescoped over 55 the extreme lower end 31 of the central member 12 until it comes into engagement with a stop pin 32. With the adjustable pole in this position the whole tent can be lifted to vertical position, the central pole acting 60 as a temporary prop. Then the three remaining telescopic poles can be telescoped over the portions 7 of the brackets 6 and swung to vertical position. When three of the poles have thus been placed in the corners, the temporary center pole can be re-

65 moved as the upper frame structure is now able to support the tent and the center pole is placed on the remaining bracket portion 7, thus providing the tent with four corner poles and leaving the center of the tent 70 free so that it may be used to better advantage.

75 As before stated, the member 14 is slideable on the short center pole 12, the purpose of which is to permit the arms 5 to be swung upwardly at an angle such as indicated by means of dotted lines in Figs. 4 and 5. This is done at times to save the tent from destructive stretching such as is likely to occur if the tent were erected when it was moist 80 or damp and then become thoroughly dried out which would tend to cause an abnormal stretching of the canvas. This abnormal pressure can be very readily relieved by simply pressing the sleeve 14 slightly upward. It is not necessary to remove any parts or 85 to loosen any nuts or other devices to accomplish this for the reason that the arms 5 are clutched on the member 12 by the pressure action before referred to. In this manner a very nice tensioning of the canvas can be secured such as will give the most satisfactory tent service without danger of imposing undue strains thereon.

90 The tent can be easily erected by a single person in a relatively short time. It can also be knocked down and the parts telescoped in such relation that the whole tent can be made into a bundle of such size that it can be carried on the running board of an 95 automobile, if desired. It will be understood that the poles 4 are telescoped entirely and that the sleeve 14 may be shoved into intimate relation with the fixture 10 when the parts are to be carried or shipped. I have thus provided a tent which is admirably adapted for use by automobilists or 100 others who desire to make and break camp frequently.

105 The many advantages of my tent will be understood by those skilled in the art to which this appertains without further comment.

I claim:

110 1. A tent of the class described embodying therein corner poles, a top supporting frame supported thereby and a canvas covering carried by said poles and top frame, said top supporting frame including a pole extending part way down from the top and 115 arm members clutched upon said pole by the action of the canvas.

120 2. A tent of the class described embodying therein corner poles, a top supporting frame supported thereby and a canvas covering carried by said poles and top frame, said top supporting frame including a pole extending downwardly from the top, 125 and arm members operatively engaging the canvas at their outer ends and having their 130

inner ends slidably supported for movement substantially in a radial direction.

3. A tent of the class described embodying therein corner poles, a top supporting frame 5 supported thereby and a canvas covering carried by said poles and top frame, said top supporting frame including a pole extending downwardly from the top, and arm members operatively engaging the canvas at 10 their outer ends and having their inner ends slidably supported for movement substantially in a radial direction, and being adapted to be raised and lowered along said centrally disposed pole.

15 4. A tent of the class described embodying therein corner poles, a top supporting frame comprising a short center pole section and radially extending canvas supporting arms and brace arms, said arms being pivotally 20 connected at their inner ends to said pole, brackets to which the outer ends of said canvas supporting arms and said brace arms are pivotally attached, said brackets being adapted for detachable connection with said 25 corner poles, and a canvas covering carried by said corner poles and top frame, said brackets including portions adapted to extend through openings in the canvas and to have secured thereto, guy members for the 30 tent.

5. A tent of the class described embodying therein corner poles, a top supporting frame comprising a short center pole section and radially extending canvas supporting arms 35 and brace arms, said canvas supporting arms being pivotally connected to the top end of center pole section and operatively connected at their outer ends to the outer ends of said brace arms and to said corner poles, 40 and a canvas covering carried by said corner poles and top frame, the inner ends of the brace arms being so connected to said center

pole section as to clutch against the same under the action of said canvas covering.

6. A tent of the class described embodying therein corner poles, a top supporting frame comprising a short center pole section and radially extending canvas supporting arms and brace arms, said canvas supporting 45 arms being pivotally connected to the top end of center pole section and operatively connected at their outer ends to the outer ends of said brace arms and to said corner poles, a canvas covering carried by said corner poles and top frame, and a sleeve 50 slidable on the bottom end of said center pole, the inner ends of said brace arms being connected to said sleeve and so engaging the center pole section as to bind against the 55 same under the action of said canvas 60 covering.

7. In combination, a tent, a plurality of tent supporting rods pivoted together near the peak of the tent, a rod carried by the junction of the said rods and having a relatively short upwardly extending portion and a longer downwardly extending portion, the said short portion engaging the peak of the tent, a collar slidably mounted on the said downwardly extending portion, a plurality 65 of tent spacing bars having their inner ends pivoted to the collar and having their outer ends engaging the corners of the tent, movement of the collar downwardly being adapted to force the bars outwardly against 70 the tent to spread and support the tent umbrella-like, and a plurality of relatively long rods adapted to engage the first mentioned rods to support the tent in raised 75 position on the ground.

In testimony whereof, I have hereunto set my hand this 23 day of May, 1924.

CHARLES B. LEFFERT.
